(57) **CLAIM**

The ornamental design for a biosignal detector, as shown and described.

DESCRIPTION

FIG. 1: Perspective

FIG. 2: Perspective

FIG. 3: Front

FIG. 4: Back

FIG. 5: Right

FIG. 6: Left

FIG. 7: Top

FIG. 8: Bottom

FIG. 9: Partial enlarged view of FIG. 1

FIG. 10: Reference view—electrodes

FIG. 11: Reference view of state in use

FIG. 12: Perspective

FIG. 13: Perspective

FIG. 14: Front

FIG. 15: Back

FIG. 16: Right

FIG. 17: Left

FIG. 18: Top

FIG. 19: Bottom

FIG. 20: Partial enlarged view of FIG. 12

FIG. 21: Reference view—electrodes; and,

FIG. 22: Reference view of state in use.

The solid lines form part of the claimed designs; the broken lines are for illustrative purposes only and form no part of the claimed designs.

1 Claim, 22 Drawing Sheets

Related U.S. Application Data

division of application No. 35/504,324, filed on Jul. 14, 2017 (U.S. filing date under 35 U.S.C. 384), and having an international filing date of Jul. 14, 2017, now Pat. No. Des. 853,569.
